UNITED STATES PATENT OFFICE.

JOHN G. SIBERT, OF SIOUX CITY, IOWA.

LAUNDRY COUNTING DEVICE.

1,413,295.

Specification of Letters Patent. Patented Apr. 18, 1922.

Application filed February 18, 1919. Serial No. 277,775.

To all whom it may concern:

Be it known that I, JOHN G. SIBERT, a citizen of the United States, and a resident of Sioux City, in the county of Woodbury 5 and State of Iowa, have invented certain new and useful Improvements in Laundry Counting Devices, of which the following is a specification.

In commercial laundries, the various operations essential to complete the laundering 10 of an article are performed, usually, by several operators, who are paid by the piece, and the articles are carried from operator to operator, or perhaps through a drying room, 15 by mechanical conveyors. It is important that the number of articles laundered be instantly ascertainable at all times, not only to determine the operators' earnings, but also to ascertain if the work is being performed with the proper expediency.

The present invention, therefore, has for its primary object the production of mechanism, operable to accurately count and register the number of articles carried by a 20 laundry-conveyor.

Furthermore, the invention contemplates a counting mechanism for a laundry-conveyor automatically actuated as articles are placed on the conveyor.

Still another object of the invention is the production of an improved laundry-counting mechanism which may be readily locked in an inoperative position.

A further object of the invention is the 30 production of an improved laundry-counting mechanism, inexpensive in construction, yet simple and thoroughly efficient and dependable in operation.

With these and other objects in view, the 40 invention, consisting in the construction, combination and novel arrangement of parts, will be fully understood from the following description, reference being had to the accompanying drawings, which form a part 45 of this application, and in which like characters of reference indicate corresponding parts throughout the several views, of which,—

Fig. 1 is a front elevation of a laundry- 50 conveyor, equipped with the preferred embodiment of the invention;

Fig. 2 is a plan of the same;

Fig. 3 is an enlarged plan of the device 55 of my invention, and the adjacent portion of the conveyor;

Fig. 4 is an enlarged front elevation of the same; Fig. 5 is a side elevation of the same, and

Fig. 6 is an enlarged side elevation of the guard and associated parts.

Although I have illustrated and herein-after described the preferred embodiment of the invention, I would not be understood as being limited to the specific structure chosen for illustration, for various alterations and modifications may be made in the details of constructions and arrangement of parts, without departing from the spirit and scope of the invention, as defined in the appended claims.

Referring, now, to the illustrations, the conveyor illustrated is a familiar type of laundry apparatus, including front and rear longitudinal channeled frame members, 6, in which travel rollers, 7, (Fig. 5), from 70 which depend hangers, 8, provided at their lower ends with outwardly-disposed hooks, 9. The said hangers are arranged in spaced relation and interconnected by an endless chain, 10, passing around sprocket-wheels, 11, journaled at opposite ends of the frame; and one of which is suitably driven. The rails, 6, are interconnected and supported by cross members, 12, and the frame is supported by uprights, 13.

Upon the hooks, 9, the operators hang the laundry articles, as shirts, collars, etcetera, whereby they are carried from the operators.

I provide a counting mechanism actuated 80 by placing the articles upon the hooks to record each article thus placed, which mechanism may consist of a movable guard member, normally so positioned as to prevent the application of articles to the conveyor without moving the guard, and a suitable counting device actuated by movement of the guard.

The structure presented embodies a familiar counting device, including a case, 14, mounted on a suitable support, 15, on the frame; and provided with a slot, 16, revealing numerals on rotating elements actuated by a reciprocating member, as the rock-shaft, 17, having a crank-arm, 18, connected by a link, 19, with one of two arms, 20, pivotally-depending from forwardly-inclined bearings, 21, mounted on the front of the frame of the conveyor. The said arms carry a guard-board, 22, normally so posi- 100 105 110

tioned as to hang directly over and closely adjacent the hanger-hooks, whereby, in placing an article on a hook below the guard-board, the operator must necessarily engage with his hand or knuckles the guard-board, as shown in Fig. 6, to force the latter rearwardly to permit application of a garment on the hook, which movement of the guard increases the number revealed by the counter one unit.

The guard is held yieldably in its normal position, as by a weight, 23, on the rear of one of the arms, 20.

To hold the device inoperative, I mount on the face of one of the arms, 20, a key-controlled lock, 24, the lock-bolt, 25, of which, when extended as shown in dotted lines in Fig. 4, engages a forwardly extending part, 26, on the adjacent bearing, 21, to prevent the guard from being swung rearwardly.

Having thus described my invention, what I claim as new and desire to secure by Letters Patent of the United States, is,—

1. A counting device for an article carrier

including a fixed support and an article support therebelow, comprising a counter, arms adapted to be mounted to pivotally depend from the fixed support, a guard board carried by the arms to prevent application of articles to said article support without swinging the arms, and an operable connection between one of the arms and the counter.

2. A counting device for an article carrier including a fixed support and an article support therebelow, comprising a counter, (upwardly extending bearings adapted to be mounted on the fixed support), arms pivotally depending therefrom, a guard board secured to the arms and so related to the article support as to prevent application of articles to the latter without swinging the arms, and an operable connection between one of the arms and the counter.

In testimony whereof I have hereunto set my hand, this 31st day of January, 1919.

JOHN G. SIBERT.
